UNITED STATES PATENT OFFICE.

HIRAM N. HUSE, OF PROVIDENCE, RHODE ISLAND, ASSIGNOR TO ST. MUNGO MANUFACTURING COMPANY OF AMERICA, OF NEWARK, NEW JERSEY, A CORPORATION OF NEW JERSEY.

MACHINE FOR COATING ARTICLES.

Application filed April 24, 1923. Serial No. 634,244.

To all whom it may concern:

Be it known that I, HIRAM N. HUSE, a citizen of the United States, and a resident of Providence, in the county of Providence and State of Rhode Island, have invented certain new and useful Improvements in Machines for Coating Articles, of which the following is a specification.

My invention relates to an improved machine adapted for spraying a coating of paint or other liquid on round or cylindrical objects, such as golf balls for example.

When objects of this character are coated by hand it is difficult to apply the coating uniformly and one of the objects of this invention is the provision of a machine which is automatic in its operation and by which golf balls for example or other cylindrical objects may be uniformly coated.

Another object of the present invention is the provision of a machine for automatically and uniformly coating cylindrical objects wherein the objects to be coated are automatically charged to and discharged from the machine so that no manual handling of the objects is necessary, means being provided whereby a number of the newly painted objects may be set to one side until dry.

A further object of my invention is the provision of means for automatically controlling the coating devices or guns so as to shut off the same after a particular object to be coated has been treated.

In general, my machine comprises a plurality of brackets or object-supporting devices mounted for rotation upon a stationary shaft so that the objects to be coated are picked up from the loading device and completely coated while travelling in the arc of a circle. The coating devices or guns are mounted so as to rotate in the same plane, on an axis coincident with the axis of rotation of the supporting brackets and in synchronism with the bodily movement of the objects being coated so that a gun is always directed towards an object as the latter passes through the coating.

As above stated, means are provided whereby the guns will be automatically started in operation as an object enters the coating zone and shut off when the coating operation is completed.

The coating guns and the apparatus for

carrying the articles to be coated are driven from the main drive shaft, this shaft also driving the loading and unloading mechanism, the whole machine being properly synchronized so as to enable the articles to be automatically charged into the machine, 60 unloaded.

In the accompanying drawings wherein I have illustrated an embodiment of my invention,

Fig. 1 shows my improved machine in part 65 sectional elevation;

Fig. 2 is an elevational view showing more or less generally the construction of the spraying devices and the control therefor as well as the details of the unloading or dis- 70 charging mechanism;

Fig. 3 is a sectional view showing the details of the spraying apparatus;

Fig. 4 is a view taken substantially on the line 4-4 of Fig. 3; 75

Fig. 5 is a plan view somewhat enlarged of the unloading mechanism; and

Fig. 6 is a section taken through Fig. 5 substantially on the line 6-6.

Referring to the drawings in detail, 1 80 designates the base of my improved machine, carrying at the upper part thereof a stationary, partially hollow shaft 2. This shaft is best seen in Fig. 3. The shaft 2 carries the coating devices or guns 3 of which there are 85 four in the present machine. It will be understood of course that the machine may be designed to vary this number if desired. The shaft 2 also supports the arms 5 carrying heads 6 upon which the objects to be 90 painted are mounted. Four guns having been illustrated in the present machine I have shown a pair of arms 5 with a head 6 at each end.

Each coating device comprises a bracket 95 7 in which the spraying device proper and which I shall designate 8 is mounted, the bracket 7 being keyed or otherwise rigidly attached to a sleeve 9 rotatably mounted upon the shaft 2. These coating devices 100 are operated by compressed air and the paint or other material with which the articles are to be coated may be led into the semi-hollow shaft 2 at 10, any suitable connection being provided between this end of the shaft and 105 a paint reservoir. The other end 11 of the shaft 2 may be connected by suitable connections to an air reservoir.

As will be seen from Fig. 1 a pipe connection is provided from the gun at one side of the brackets or arms 5 to a corresponding gun on the opposite side by the pipe 12 which may be for air or coating material as the case may be and a similar connection is provided by the pipe 13. In other words, conduits for coating material are provided between the guns on each side of the arms 5 or brackets 5 so that the supply of air may all be led into the machine at one end of the shaft 2 while the coating material may be fed into the other end of said shaft.

Air under pressure may pass into the end 11 of the shaft 2 and through the shaft to the controlling mechanism at the point 14. At this point a port 15 is provided in the shaft 2 this port being in communication at all times with the pipes 16, in turn adapted to be placed in communication with the pipes 12. The pipes 16 communicate directly with the coating device 8 at one side of the arms 5 and by means of the pipe 12 with a corresponding coating device on the other side of said arm. This permits of a supply of air under pressure to spraying devices on each side of the arms 5 simultaneously and similar means are provided for supplying coating material to coating devices on each side of the arms 5 the coating material being led as above pointed out through the end 10 of the shaft 2 through the shaft until it reaches port 17 which port is in communication with pipes 18 similar to the pipes 16 already referred to, these pipes also communicating with the pipe 13 passing over to and communicating with the coating devices at the left-hand side of the arms 5 as viewed in Fig. 1. This permits of a supply of paint or other coating material to be fed to coating devices on each side of the arms 5 simultaneously.

The discharge of the coating material is controlled by the mechanism shown in detail in Fig. 2, the operation of this mechanism properly timed being synchronous with respect to the other operating parts of the machine.

From Fig. 2 it will be seen that each coating device or gun is provided with trigger mechanism comprising a pivoted valve-controlling lever 19 pivoted at 20, and provided at one end with a roller 21 adapted to cooperate with a cam track 22. The opposite end of this lever is engaged by a pivoted bell crank lever 23 which in turn cooperates with a stationary cam 24 mounted upon the shaft 2. As the coating devices are rotated in a manner to be hereinafter described, the cam track 20 and stationary cam 24 will cause the valve-controlling lever 19 through the medium of the roller 21 and bell crank lever 23 to be rocked about its pivot to automatically shut off and open the valves of the coating devices so as to

permit of the coating material to be discharged from the spraying devices for a predetermined length of time and then to be automatically shut off until a new article to be coated enters the coating zone.

Rotation of the coating device about the shaft 2 is effected through the medium of a gear 25 mounted upon the sleeve 9 at the right of Fig. 1, this sleeve being keyed to the bracket 3 supporting the spraying devices 75 on the right side of the arms 5 (see Fig. 3) a connection, to wit a sleeve 26, being provided between this bracket and the bracket 3 at the left of the arms 5. Rotation therefore of the gear 25 will rotate the coating devices on both sides of the arms 5 simultaneously. The gear 25 meshes with a gear 26 carried by a shaft 27 this shaft carrying a sprocket or a chain 28 the other end of which is carried by a sprocket mounted 85 upon the main drive shaft 29.

The arms 5 are keyed or otherwise rigidly attached to the sleeve 26 and as a consequence these arms will be rotated as a unit with the coating devices and about the same 90 axis.

Referring again to Fig. 1, it will be seen that each head 6 is provided with a spindle 30 the lower end of which carries a gear 31, the upper end carrying article-supporting 95 prongs 32 for carrying a ball or other article B to be coated. The gear 31 meshes with an intermediate gear 32 also carried by the head 6 and a gear 33, the latter carrying a spindle 34 on which is mounted a bevelled gear 35. The spindle 34 extends vertically and the gear 35 is in constant mesh with a bevelled gear 36 carried by a horizontally extending shaft 37 passing through the ends 105 of the arms 5, this shaft also supporting the head 6. I have in effect therefore suspended the heads 6 from the ends of the horizontally extending shaft 37 and as the arms 5 are rotated to carry the heads in an arc of a circle 110 the gears 31, 32, 33, 35 and 36 will impart rotation about a vertical axis to the spindles 30 as the head tends to maintain itself in a vertical position by gravity, to thereby also impart rotation to the ball and the head 6 about the axis of the shaft 37. This motion 115 of the spindles 30 about a vertical axis is made positive by the provision of chains 38 passing over a sprocket 39 on the sleeve 26 and a sprocket on the shaft 37.

Discharging or unloading mechanism.

The mechanism for discharging the coated articles from the machine is best shown in Figs. 2, 5 and 6 and will now be described. Inasmuch as the articles to be coated are 125 operated upon at both sides of the brackets 5 simultaneously I find it convenient and desirable to provide two sets of unloading mechanism, these sets being duplicates of each other. Referring therefore to the un- 130

loading mechanism shown at the left of Fig. 1 for example, it will be seen that the drive shaft 29 carries a cam 40 this cam cooperating with a series of lugs 41, twelve 5 in all, on the underside of a plate 42 which is mounted upon a vertically extending shaft 43.

Connected to the plate 42 in any suitable manner as by a key for example, is a gear 44 this gear meshing with three other gears 45, 46 and 47. The gears 45, 46 and 47 are carried at the lower ends of short shafts 48, 49 and 50 respectively, these short shafts being in turn carried by arms 51, 52 and 53 15 which are mounted for simultaneous, in fact unitary rotation, upon the shaft 43.

Adjacent the upper ends of the shafts 48, 49 and 50 I provide sleeves 54, 55 and 56 respectively, each keyed to its shaft, these 20 sleeves being provided for the purpose of driving discharging plates 57, 58 and 59 respectively. Each of these plates, as will be seen from Fig. 5, is provided with cutouts 60, these cutouts being arranged in the periphery of the plates or adjacent the periphery for the purpose of removing the 25 coated articles from the spindles 30. Each plate is provided with a hub 61 adapted to cooperate with an extension 61' which is provided on the upper face of a clutch 62 on which the plates are supported cooperating with the sleeves 54, 55 and 56 respectively.

In the present machine the plates 57, 58 35 and 59 are provided with twelve of the cutouts 60 and these cutouts are moved successively into position to receive a coated article by plate-advancing mechanism 48 comprising a mutilated gear 63 on the shaft 43 which meshes with a gear 64 on the shaft 43 carrying the plate 42. The cam 40 on the drive shaft 29 is so arranged and so cooperates with the lugs 41 that each time the cam makes one revolution the plate 42 and hence 40 the plates 57, 58 and 59 will be given one-twelfth of a revolution. Assuming that the plate 59 is in discharging or unloading position, at each revolution of the cam 40 an opening 60 will be brought into proper position to remove a coated article from one of the spindles 30. When this plate becomes 45 fully loaded the mutilated gear 63 will have been moved into mesh with the gear 64, and the gear ratio between the mutilated gear 63 and the gear 64 is such that this meshing of these two gears will move the arms 51, 52 and 53 part of a revolution about the shaft 43 to bring the next plate 58 into discharging or unloading position and carrying the plate 59 out of such a position. After the plate 58 becomes fully loaded the plate 57 will be automatically moved to unloading position. In the meantime the loaded plates may be removed and replaced 60 with empty plates.

Loading mechanism.

Means are provided in the present machine for automatically feeding or loading the articles to be coated to the machine. At 70 the bottom of the machine and mounted in bearings in the uprights of the machine I provide a shaft 65 carrying segmental gears 66 one at each end of the shaft. Referring to the mechanism at the right of Fig. 1, the gear 66 meshes with a rack 67 which is attached to or forms an integral part of a loading slide 68. This same shaft 65 carries a segmental gear 69 meshing with a segmental gear 70 the latter being pivoted at 71 and 75 attached to an arm or lever 72 on the same pivot, the other end of this lever carrying a roller 73 which rides in a cam slot 74. From Fig. 2 it will be seen that as the cam which is provided with the cam slot 74 is rotated 80 the arm or lever 72 will be given a rocking motion which motion will be imparted to the segmental gear 66 and from thence to the loading slide 68. The slide 68 cooperates with the bottom of a loading tube 75 85 which is connected to a hopper (not shown) and as the ball or other article to be coated is fed down through this tube 75 a ball will be deposited upon the loading slide 68 provided the slide is in the position shown in Fig. 2. 90 As the arm 72 is actuated this slide is moved to the right as viewed in Fig. 2 carrying the ball thereon along with it. It will be noticed from Fig. 2 that this slide is provided with a raised portion or shoulder 76 and this 95 acts as a stop when the slide is in its forward or loading position to prevent discharge of the balls from the tube 75 upon the slide. Of course the movement of this slide is 100 timed properly with the various other movements of the machine so that it goes forward into position to load a ball into the machine as one of the heads 6 moves into position to receive it.

Operation of the machine.

Assuming that the parts are all in the position shown in Fig. 1 for example, if the machine be set in motion the loading slide 68 will be moved forward or to the right as viewed in Fig. 2 into position to carry forward an uncoated article and to close off the end of the loading tube 75. It is to be understood that there are two loading tubes one at each side of the arms 5 and that the operation of the mechanism at one side of the arms is identical with the operation of the mechanism at the other side of these arms and consequently both loading slides 115 are moved forward simultaneously. As the arms 5 carrying their respective heads 6 are rotated about the shaft 2 the spindles 30 carried by the heads are moved upward beneath the ball on each of the loading slides 120 68, and as the heads and their spindles con-

tinue their upward motion they will finally pick up the articles to be coated from the slides carrying them upwardly in the arc of a circle.

5 It is to be borne in mind that the coating devices are always in a fixed position with respect to the outer ends of the arms 5.

As the articles to be coated are moved in their arcuate path the coating devices are 10 also moved therewith in other words are caused to follow the articles, and as the articles enter the coating zone the cam 24 and the cam track 22 cooperating with the lever 23 and the lever 19 respectively open the 15 valves of a pair of the coating devices, one on each side of the arms 5, to permit the paint or other coating material to be discharged upon the articles on spindles 30. The spindles 30 it must be remembered at 20 this time are not only being moved in the arc of a circle about an axis coincident with the axis of rotation of the spraying device but they are also being rotated individually about a vertical axis due to the action of 25 the gears 31, 32, 33, 35 and 36 so that the articles during the spraying operation are presenting constantly changing surfaces to the action of the coating devices. Finally after the articles have reached a predetermined 30 position in their travel the valve mechanism of the coating devices will be closed automatically and the coating operation will cease.

The articles, however, continue their arcuate movement and finally will be brought 35 into register with an opening in one of the unloading plates. The spindle 30 passes down through one of these openings and the articles will be deposited upon the plate.

40 During this operation the loading slides 68 have been returned to position beneath the loading tubes 75 to receive fresh articles from said tubes and the spindles carried by the ends of the arms 5 opposite to these ends 45 which are carrying the articles which have just been coated will have moved around into position to pick up these fresh articles from the loading slides, so that before the coated articles have been discharged from 50 the conveying mechanism new articles will have been started on their journal toward the coating zone. The second load of articles to be coated goes through the same operation as that described in connection with 55 the first load, being finally deposited on the discharging or unloading plates. By the time this second load of articles reaches the unloading plates the latter will have been moved one-twelfth of a revolution due to 60 the action of the cam 40 and its cooperating lugs 41 so as to bring openings 60 into position to receive this second load of articles from the conveying mechanism. The loading 65 of the articles into the machine, coating them and then discharging them upon the

unloading plates continues until plates on each side of the arms 5 have been completely filled. At this time the mutilated gear 63 will have been rotated into mesh with the gear 64 and will give the arms 51, 52 and 70 53 a partial rotation about the shaft 43 to bring a pair of empty unloading plates into position to be filled.

The filled plates are designed so that upon their removal from the machine they may be 75 arranged in stacks the bottom of a plate with its load of freshly coated articles resting upon the hub 61 formed on the upper surface of each plate, this hub maintaining 80 the plates spaced from each other to permit the articles to dry without coming in contact with each other.

It will be seen therefore that I have provided a machine adapted to coat objects, particularly spherical objects such as golf 85 balls for example, which is full automatic in its operation wherein the devices and the articles to be coated are moved in parallel arcuate paths and in which the coating devices are rotated about an axis which is coincident with the axis about which the articles to be coated are rotated. In addition to this bodily movement the articles are rotated about a vertical axis, each article being 90 rotated about an individual axis, so that in passing through the coating zone the articles present a constantly changing surface to the action of the coating devices. This arrangement 95 insures uniform coating of the articles.

It will be seen also that in the present 100 machine I have provided mechanism which is arranged so that the machine is loaded automatically, means being provided as above pointed out to prevent more than the desired number of articles being charged 105 into the machine at one time.

It will be clearly understood also from the foregoing description that the coating devices are automatically controlled so far as their operation is concerned so as automatically to begin the coating operation as the article enters the coating zone and to be automatically shut off when the coating operation is completed.

110 It is to be understood that the design of this machine may be varied without departing from the spirit and scope of my invention and that the number of articles which may be coated simultaneously may be varied if desired, the number of articles so coated 115 in the above description having been used by way of illustration only.

1 claim:

1. In a coating machine, means for holding 125 an article to be coated, a coating device and means for moving the article and the coating device in the same plane in arcuate parallel paths.

2. In a coating machine, means for holding 130 an article to be coated, a spraying de-

- vice, means for moving the spraying device and the article simultaneously in the same plane in parallel arcuate paths and to impart a rotary motion to the article about its individual axis.
3. In a coating machine, rotary means for holding an article to be coated, a coating device, means for rotating the coating device about an axis coincident with the axis of rotation of the article-holding means and means for rotating the article about an axis at an angle to the axis of rotation of the coating device.
4. In a machine for coating articles, means for holding an article to be coated during the coating operation, a coating device, means for moving the coating device about an axis, and means for moving the article bodily about an axis parallel to the axis of movement of the coating device while the article is being given a movement about an axis disposed at an angle to the axis of movement of the coating device.
5. In a machine for coating articles, a support, an arm carried thereby and rotatable thereon, a coating device rotatable on said support, an article-carrying device at the outer end of said arm and means for rotating said arm and said coating device about said support to cause the coating device and the article carried by said arm to be moved in the same plane in parallel arcuate paths.
6. In a machine for coating articles, the combination of an article-supporting device, a coating device, means for moving the article-supporting device and the coating device in the same plane in parallel arcuate paths and means for automatically controlling the operation of said coating device to cause the coating device to operate only throughout a part of the travel of said article-carrying device.
7. In a machine for coating articles, the combination of an article-carrying spindle, means for moving said spindle with an article carried thereby through a coating zone, and an unloading plate, said spindle in its travel passing through an opening in said unloading plate to remove the coated article from the spindle.
8. In a machine for coating articles, the combination of means for conveying articles to be coated through a coating zone, a series of unloading plates adapted to receive the coated article and means for periodically advancing an unloading plate to unloading position while simultaneously moving a filled plate from unloading position.
9. A machine for coating articles comprising means for conveying articles to be coated through a coating zone, an unloading plate in the path of travel of the coated article, a drive shaft for driving the conveying means for the articles to be coated and said unloading plate, a cam on said drive shaft, a plate, lugs carried thereby and cooperating with said cam, said plate being operatively connected to the unloading plate whereby upon rotation of said drive shaft the unloading plate will be rotated periodically to advance successive predetermined portions of the plate into position to receive the coated articles.
10. In a machine for coating articles, the combination of conveying means for carrying articles to be coated through a coating zone, a plurality of unloading plates adapted to receive coated articles from said conveying means, a common support for said unloading plates, a common driving means for said conveying mechanism and said supporting plates, cam mechanism driven by said driving means and adapted to rotate one of said unloading plates to interpose predetermined portions thereof in the path of the coated articles, and gearing driven by said driving mechanism for actuating one of said plates out of article-receiving position and to move the other plate into receiving or unloading position.
11. In a machine for coating articles, unloading mechanism comprising a rotatable arm, a sleeve carried thereby, a shaft extending vertically through said sleeve, a clutch member supported on said sleeve, an unloading plate carried by said clutch member and provided with a projection on the face thereof cooperating with an extension on said clutch member whereby lateral displacement of the unloading plate with respect to the clutch member is prevented, said plate being provided with openings symmetrically arranged in the face thereof and adapted to receive the coated articles.
12. In a machine for coating articles, unloading mechanism comprising a rotatable plate, lugs carried thereby, cam mechanism cooperating with said lugs, a gear operatively connected to said plates, a pair of arms rotatably supported in axial alignment with said plate, an unloading plate carried by each arm, a gear operatively connected to each of said unloading plates and to the first-mentioned gear whereby upon actuation of the lug-carrying plate by said cam the unloading plates will be rotated a part of a revolution, and a mutilated gear operatively connected to said lug-carrying plate adapted to simultaneously swing one of said unloading plates out of unloading position and the other of said plates to unloading position.
13. In a machine for coating articles, a shaft, an arm rotatable thereon, a system of gears at the outer end of said arm, a stub shaft carried on said arm and in axial alignment with said gear, a head suspended from the outer end of said stub shaft, a spindle constituting a part of said head, a gear on

- said spindle and in mesh with said system of gears, article-supporting prongs carried by said head and adapted to be driven from said spindle whereby when said arm is rotated an article carried by said prongs will be moved in the arc of a circle and simultaneously rotated about a vertical axis.
14. In a machine for coating articles, the combination of means for conveying an article to be coated through a coating zone, a loading trough, a loading slide cooperating therewith and with said conveying mechanism to simultaneously advance the article to be coated in the path of said conveying mechanism and to block said loading trough, a drive shaft for said conveying mechanism and a gear driven from said shaft for reciprocating said loading slide.
15. In a machine for coating articles, the combination of mechanism for carrying articles to be coated through a coating zone, and loading mechanism automatically operable to present an article to said conveying mechanism periodically, said loading mechanism being timed with respect to the conveying mechanism so as to advance an article to loading position as the conveying mechanism reaches a predetermined point in its travel.
16. In a machine for coating articles, an unloading trough, an unloading slide cooperating therewith, a rack connected to said slide, a quadrant meshing with said rack, cam mechanism for oscillating said quadrant to reciprocate said slide, conveying mechanism for conveying the articles to be coated and adapted to receive such articles from said slide, said slide and conveying mechanism being so timed that as the conveying mechanism reaches a predetermined point in its travel the slide will be moved into position to present an article to be coated thereto, said slide at the same time blocking said loading trough to prevent the discharge at that instant of an additional article therefrom.
- This specification signed this 19th day of April 1923.

HIRAM N. HUSE.
